UNITED STATES PATENT OFFICE.

JAMES H. BOYE, OF CHICAGO, ILLINOIS, ASSIGNOR TO JAMES H. BOYE MANUFACTURING COMPANY, OF CHICAGO, ILLINOIS, A CORPORATION OF ILLINOIS.

ADJUSTABLE SASH-CURTAIN SUPPORT.

1,298,286.

Specification of Letters Patent. Patented Mar. 25, 1919.

Application filed June 13, 1918. Serial No. 239,713.

To all whom it may concern:

Be it known that I, JAMES H. BOYE, a citizen of the United States, residing at Chicago, in the county of Cook and State 5 of Illinois, have invented certain new and useful Improvements in Adjustable Sash-Curtain Supports, of which the following is a specification.

This invention relates to supports for 10 sash curtains for bath-room and other windows, which are usually so made as to be readily removable from the window and are also frequently made adjustable in point of length so as to fit windows of varying widths.

15 The principal objects of the present invention are, to provide a sash curtain support having a wide range of adjustability as to length; to provide a sash curtain support that will not bind or sag when in use; 20 to provide a sash curtain support that may be very easily assembled, mounted and adjusted; and, generally, to provide an improved sash curtain support of simple, strong, durable and economical construction 25 and possessing a neat and trim appearance.

These and other objects and advantages of the invention will be apparent to those skilled in the art from the following detail description, taken in connection with the 30 accompanying drawing in which I have illustrated a practical and preferred embodiment of the invention, and wherein—

Figure 1 is a front elevation of my improved sash curtain support, shown as 35 mounted between the upright side members of a window frame;

Fig. 2 is an enlarged view of the left hand portion of Fig. 1, as viewed from beneath the latter;

40 Figs. 3 and 4 are fragmentary detail views illustrating the manner of assembling and locking the intermediate section of the support with one of the end sections;

Fig. 5 is a section on the line 5—5 of Fig. 45 4; and

Fig. 6 is a fragmentary detail showing the bracket which carries the attaching hook secured to the outer face of the upright of the window frame.

50 Referring to the drawing, 7 designates a flexible rod which constitutes the intermediate and principal length of the support, and, in the instance shown, is formed of closely coiled wire so as to possess an elastically extensible character as well as trans-

verse flexibility. 8 designates as an entirety each of the end sections, the same being of tubular structure, cheaply rolled to form from a flat sheet-metal blank on a suitable mandrel or otherwise, and of a size to permit the intermediate section 7 to be readily telescoped therein. At its inner end the tubular section 8 is provided with a lateral opening or slot 9 which may be formed by cutting away some of the metal of the tube 60 on its lower side for some distance inwardly of the inner end of the latter. The opposite sides of the tube at the open end of the side opening or slot 9 are bent or swaged inwardly, forming teeth 10. At its outer end 70 the tube is formed with a slightly widened and partially flattened end extension 11 which is slotted lengthwise to form an eye 12 that may be readily engaged with and disengaged from a hook 13 struck up from 75 an attaching plate or bracket 14; this latter being secured either to the transverse face 15 (Fig. 1) or to the outer face 16 (Fig. 6) of one of the upright side members 80 of the window frame.

To assemble the sections of the curtain support, one end of the middle section 7 is entered through the side opening 9 of one of the tubular end sections 8 in the manner clearly shown in Fig. 3 and inserted into the 85 latter to any desired or necessary extent, the flexibility of the member 7 readily permitting this to be done. With a slight pressure of the thumb and finger the parts 7 and 8 are then pressed side-wise until they are 90 brought into substantial alinement; and during this operation the teeth 10 are forced into gripping or biting engagement with the member 7, entering between adjacent coils on opposite sides of the latter, and strongly locking the sections 7 and 8 against relative sliding movement. The other end of the member 7 is then similarly engaged with the other end member 8, and the eyes 12 of the 95 end members 8 are then engaged with the hooks 13 in an obvious manner. The assembled structure is preferably applied to the window with the intermediate section 7 stretched sufficiently to give the structure a 100 perfectly straight and level form and prevent any bending or sagging.

The lateral opening 9 through which the intermediate member 7 is inserted and withdrawn is preferably formed on the lower side 105 of the end member 8, as shown. This loca- 110

tion of the lateral opening has the advantage that if, in assembling the parts, the members 7 and 8 should not be pressed together sufficiently to insure the full gripping action of the teeth 10, when the curtain is in place and is pulled down in adjusting the same on the support, the tendency of such action is to bring the parts 7 and 8 into fully interlocked engagement.

10 From the foregoing it is believed that the nature, structure, mode of manipulation and advantages of the invention, and manner in which the stated objects are secured, will be readily apparent to those familiar with the art without further description. It is evident that changes and modifications in the details of structure and arrangement herein shown may be made without departing from the structural principle of the device or sacrificing any of the advantages secured thereby. Hence, I reserve all such modifications as fall within the spirit and purview of the appended claims.

I claim:

25 1. An adjustable sash curtain support, comprising a flexible rod forming the intermediate section of the support, and tubular end sections, each of said end sections being formed with a side opening adjacent to its inner end through which said flexible rod may be inserted and withdrawn and with means for automatically gripping said rod when it is brought into alignment with the end section.

30 2. An adjustable sash curtain support, comprising a flexible rod forming the intermedi-

ate section of the support, and tubular end sections, each of said end sections being formed with a side opening adjacent to its inner end through which said flexible rod 40 may be inserted and withdrawn and with inwardly bent teeth at its inner end adapted to grip the sides of said rod when the latter is brought into alignment with the end section.

3. An adjustable sash curtain support, comprising a rod formed of closely coiled wire constituting the intermediate section of the support, and tubular end sections, each of said end sections being formed with a side 50 opening adjacent to its inner end through which said rod may be inserted and withdrawn and with inwardly bent teeth at its inner end adapted to grip the sides of said rod between adjacent coils when the rod is 55 brought into alignment with the end section.

4. An adjustable sash curtain support, comprising a rod formed of closely coiled wire constituting the intermediate section of the support, and tubular end sections, each of 60 said end sections being formed with a side opening extending inwardly from its inner end sufficiently to permit the insertion and withdrawal of said rod therethrough and with inwardly bent teeth adapted to grip the 65 sides of said rod between adjacent coils when the rod is brought into alignment with the end section, and also at its outer end with one member of a hook and eye connection to an element of a window frame.

JAMES H. BOYE.
